UNITED STATES PATENT OFFICE.

MANUEL PARDO Y COSIO, OF MADRID, SPAIN.

AIRSHIP.

Application filed December 24, 1920. Serial No. 432,975.

To all whom it may concern:

Be it known that I, MANUEL PARDO Y Cosio, an engineer, and a citizen of Mexico, residing at Madrid, Spain, Hotel Cervantes, Carrera de San Jeronimo 43, have invented certain new and useful Improvements in Airships, of which the following is a specification.

The present invention consists in varying the total area of the supporting surfaces of a biplane, as well as the coefficient of the supporting property of this total, with the object of increasing the speed of movement of the aeroplane; and in adding some arrangements by means of which, notwithstanding the said variations, the stability and the noxious surface value are maintained.

The fundamental formula governing the support of an aeroplane is:

$$V = \sqrt{\frac{P}{KS^i}}$$

where V is the speed in metres per second; P the total weight in kilogrammes; K the coefficient of the supporting power of the sum total of surfaces; S the sum of the areas of the supporting planes; and i the angle of inclination.

If in this formula, considering P and i to be constant, K is divided by a certain value, as well as S , the fraction under the root will become multiplied by the product of these divisors—which latter may be equal or different—and the second member of the equation will be multiplied by the square root of this product, with the result that the value of V will be multiplied.

An increase in the velocity implies an increase in the effective power necessary to support the apparatus. The formula relating thereto is:

$$Tu = \frac{Vt}{75}$$

where Tu is the effective or useful power; V the speed; and t the traction.

If V is multiplied by a certain value, the power Tu is multiplied by the same value;

On the other hand, the value of t increases slightly by the formula:

$$t = P \left(i + \frac{0.08s}{KS^i} \right)$$

where t is the traction; P the total weight;

i the angle of inclination; s the noxious surface; K the supporting power of the planes; and S the sum total of the areas of the supporting planes.

The increase is due to the fact that the noxious surface is multiplied by a factor and the quantities K and S are divided. As the variations act upon an addendum, the modifications in the value of t are slight. Nevertheless, they have been taken into account, for the purpose of applying a part of the power Tu which is not transformable into speed, towards overcoming the new resistance to advance, slight though it may be.

The aim of aviation has always been to utilize the whole power of the engine during horizontal flight and to transform into speed the excess of power used for ascent. Hitherto this has been impossible, owing partly to the fact that it is not feasible to use any angle of inclination, and partly because the necessity of varying the area of the supporting surfaces during flight has not been hitherto solved. The engine necessarily works at reduced pressure, during horizontal flight, the surplus power available being of considerable value.

For the purpose of transforming this surplus into speed, it is advisable to make the area of the supporting surfaces variable at will, but without exceeding the limit of the usual loads per square metre of supporting plane. In order not to pass beyond this limit, it is advisable to introduce the modification not only in the aforementioned area but also in the coefficient of support of the planes.

This is achieved by means of the present invention.

The invention is here disclosed as applied to biplanes, because a biplane provides the framework constituting the transversal body of the apparatus, which affords means of fixing the structures on a solid basis. In a monoplane, the dead-weight would have to be increased considerably by adding new arrangements of adjustment; whereas in a biplane we reckon with practically the same original material.

The following is a brief description of the invention.

The lower wing of the biplane is divided into sections or parts, the longitudinal axis of which is parallel to the longitudinal

symmetric axis of the apparatus. These parts may be of variable width, according to conditions; and some of them are raised a little above the original plane and can be moved parallel to themselves—those on the left in an opposite direction to those on the right, so as to keep the centre of gravity of the system in the same position—just as if the black keys of a piano could be displaced sideways. In uncovering the apertures that are left underneath them, they thus reduce the area of the lower plane. As the remaining part of the wing is formed of planes presenting the lesser edge in length, the coefficient of supporting power of the lower plane is thus varied.

In the drawings attached hereto, the distance between the uprights of the framework, for each part of it, has been taken as two metres. For each one of these open spaces the movable part or section is given a width of sixty-six centimetres, leaving one metre and thirty-four centimetres for each fixed part or section.

The movable parts or sections can be made to slide by means of a control worked by a wheel within reach of the pilot.

In said drawings:

Figure 1 is a side elevation of an aeroplane equipped with the invention.

Fig. 2 is a front elevation.

Fig. 3 is an enlarged plan view of the forward portion of the aeroplane.

Fig. 4 is a view similar to Fig. 1, but showing certain modifications.

Fig. 5 is a plan view of the rear portion of the aeroplane represented in Fig. 4.

Fig. 6 is a plan view of the rear portion of the aeroplane represented in Fig. 3.

Referring more particularly to the drawings, the steering wheel 1 is secured to a horizontal rod 2, which is journaled in suitable bearings located in the nacelle, one of the bearings being indicated at 19. The rod 2 carries at its forward end a worm 3 in mesh with a worm wheel 4 on the upper portion of a vertical shaft 5 which is also journaled in bearings in the nacelle; said shaft carrying at its lower end two grooved pulleys 6 and 7, around which pass the wires or cables 10 and 37 for controlling the movements of the sliding sections or parts 12 of the lower wing or plane. There is one of these movable sections at each side of the fuselage, and each of them is suitably connected to the respective branch of the cable corresponding to the side of the fuselage on which the section is located, either the cable 10 or the cable 37; the cables passing around pulleys 34 at the extreme ends of the plane, and around guide pulleys 8 and 9 located adjacent pulley 6, and a guide pulley 11 located adjacent pulley 7. Hence, when the steering wheel 1 is turned, both pulleys 6

and 7, will be rotated, and their associated cables 10 and 37 thereby driven, thus shifting the sections or parts 12 simultaneously; said sections moving either toward or from each other according to the direction in which the steering wheel is turned.

In the construction illustrated, each movable section 12 is slidably connected with front and rear guide bars 13 and 35 (Fig. 2), the ends of which are supported in collars 14 fixed to the lower parts of the usual uprights comprised in the rigging or framework. The sections are provided at their longitudinal edges with partitions or walls 16, to prevent the escape of wind along said edges and thereby maintain the same degree of support for the plane or wing when the movable sections are either superposed or non-superposed.

These partitions, however, do not render the sections celliform, because they terminate short of the stationary part or body of the plane. Each movable section carries a pair of cross-sleeves 38 (Fig. 3) for engagement with the guide rods 13 and 35; and these sleeves fit over said rods and are supported at their ends in openings in the section walls 16, and they are adapted to contain a lining 39 of cloth soaked with a lubricant. Additional supports 41 and 42 may be provided for the two front rods 13, which supports may also serve as stops to limit the movements of the sections in opposite directions; and there may also be provided, in connection with each section, a wind-shield 15 which is fastened to the front beam of the wing or plane at such a point as to be disposed directly in front of the corresponding section when the latter occupies its superposed position upon the fixed part or body of the plane.

The screens take the shape of a forwardly-directed V or angle, as represented in Fig. 1; and their function is to prevent the passage of air currents between the movable sections and the body of the plane when the former occupy their previously-mentioned superposed position.

The rotary movement of the steering wheel 1 and its rod or shaft 2 is also utilized to adjust the position of the movable section of the tail-stabilizer. This section, which is indicated at 27 in Figs. 1 and 6, is adapted to be shifted into and out of superposed or overlapping relation to the fixed forward portion 30 of the stabilizer by means of a control bar 23, connected at its front end to the adjacent stretch of a cable 21, as hereinafter explained; said bar being mounted to slide in guides 25, 24, 26 suitably attached to the fuselage. The section 27 itself is mounted to slide in elongated guide loops or runners 29, likewise suitably fastened to the fuselage and it has hinged to its rear edge the depth rudder 28.

The operating cable 21 for the movable section 27 passes at its forward end around the grooved periphery of a bevel gear 18 mounted on a stub shaft in the nacelle and meshing with another bevel gear 17 fixed on the extreme upper end of shaft 5. The two stretches of the cable extend downward from the pulley gear 18, and are led beneath guide pulleys 36 mounted on a bracket 43 at the bottom of the nacelle. From the pulleys 36 they are led rearwardly into and through the fuselage, passing successively around the guide pulleys 31, 32 and 33, the last-mentioned pulley being mounted on a bracket 20 located in the rear portion of the fuselage. Between the pulleys 32 and 33, the two stretches of the cable diverge somewhat in a vertical direction, the front end of the control bar being fastened to the upper stretch. The lower stretch is designed to have connected to it at the point 22 a suitable balance weight which is shifted by the movement of the cable to maintain the center of gravity constant with relation to the movable section of the stabilizer during the adjustment of said section, the latter and the balance weight moving in opposite directions by virtue of the relative arrangement of the stretches to which they are respectively attached.

In the modified construction represented in Figs. 4 and 5, the bevel gears 17 and 18 are omitted, and their place is taken by a single grooved pulley 45 fixed to the lower end of the vertical transmission shaft 5. The cable 21 passes around this pulley and then extends rearwardly around the pulleys 31, 32 and 33; the heavy bracket for the last-named pulley being replaced by light strap brackets, as shown in Fig. 4. The movable section 46 of the stabilizer is mounted to slide in runners 29', as in the first construction, which runners are fixed to supporting brackets 47 (Fig. 5) attached to the fuselage, which term is here employed, as also in its previous occurrences, to indicate not only the body proper of the airship, but also the beams or framework thereof. Said section 47, which is operated, as before, by a control rod 23, is considerably narrower than the corresponding section 27 in the first construction and is located closer to the center of gravity of the ship; but it is entirely independent of the depth rudder 28' which instead of being connected to it, is hinged to the fixed part or member 30', the result being that the pilot can operate the two controls independently, viz: that of stability as produced by the depth rudder, and that of stability as resulting from the equation of momenta when the surface area of the lower plane is varied consequent upon the adjustment of the movable section 12. The guide pulleys 36 and their supporting

bracket 43 are likewise omitted from the modified construction; and one of the guides for the control rod is also omitted because of the shorter length of said rod. Hence, it will be apparent that the modified construction, while operating in the same general manner as the first construction, is simpler and lighter by reason of the omission of the parts specified.

Working.

75

During the flight, working is begun with the movable parts of the lower plane covering the openings and with the surface of the stabilizer normal, and is ended with the movable parts of the lower plane uncovering the openings and the stabilizers reduced. To reverse, the work is begun with the movable parts of the lower plane uncovering the openings and with the stabilizer reduced, and is ended having the movable parts covering the openings and with the surface of the stabilizer normal.

When the wing becomes reduced in size the stabilizer is reduced; when the wing returns to its normal size, the stabilizer returns to its normal size. Wing and stabilizer are small at the same time or large at the same time. This movement of contraction or of extension allows the speed to be increased or reduced: to increase it if the planes become smaller, to reduce it if the planes grow larger.

The ground is left with the wing and stabilizer extended, starting at a chosen speed; during ascent the steering wheel is not worked; when a height is reached at which flight is to be horizontal, pressure is reduced and the depth rudder worked. The flight being horizontal with the ruling speed, pressure is increased, and simultaneously—as far as possible—the wheel is worked to reduce the area of the lower plane. Progressively, at the discretion of the pilot, the new conditions of supporting surface and of power of this surface are created, and the speed attained that satisfies the equation of support; this without changing the angle of inclination, but keeping it at the value at which horizontal flight was begun. Then maximum speed will be obtained, since, for a given apparatus, the minimum surface and the minimum coefficient of power will have been reached. The operation may be stopped, at will; it may not be commenced; or not be terminated; as the pilot desires, having regard only to the effective power available. The control of the depth rudder is independent and may be used when desired or needed; the same applies to the steering rudder, the small wings and the buckling-surface.

I claim as my invention:—

1. In an airship, a plane having symmetrical openings at opposite sides of and

parallel with its transverse axis and extending substantially the entire width or fore-and-aft distance of the plane, and movable sections corresponding in size and shape to said openings for covering or uncovering the same to increase or decrease the surface area of the plane, said sections being disposed slightly above the plane; and means for moving the sections in unison in either direction at will independently of the movements of the plane.

2. In an airship, a plane having symmetrical openings at opposite sides of and parallel with its transverse axis and extending substantially the entire width or fore-and-aft distance of the plane, movable sections corresponding in size and shape to said openings for covering or uncovering the same to increase or decrease the surface area of the plane, said sections being disposed slightly above the plane, and front and rear longitudinal guide bars for the sections mounted upon the plane at opposite sides of the fuselage and with which said sections are slidably connected; and means for moving the sections in unison in either direction at will independently of the movements of the plane.

3. In an airship, a plane having symmetrical openings at opposite sides of its transverse axis, and movable sections corresponding in size and shape to said openings for covering and uncovering the same, said sections being disposed slightly above the plane; a wind-shield of forwardly-directed V-section attached to the front edge of the plane immediately to one side of each opening so as to prevent the entrance of wind between the corresponding movable section and the plane when the former uncovers the opening; and operating means for said sections.

4. In an airship, a plane having symmetrical openings at opposite sides of and parallel with its transverse axis and extending substantially the entire width or fore-and-aft distance of the plane, and movable sections corresponding in size and shape to said openings for covering or uncovering the same to increase or decrease the surface area of the plane, said sections being disposed slightly above the plane and having depending partition walls at their side edges which terminate short of the upper surface of the plane; and operating means for said sections.

5. In an airship, a plane having symmetrical openings at opposite sides of its transverse axis, and movable sections corresponding in size and shape to said openings for covering and uncovering the same; a steering rod and wheel; a vertical shaft; a gear connection between the steering rod and vertical shaft; a pair of superposed pulleys secured

to the lower portion of said shaft; a pair of pulleys mounted on the extreme ends of the plane; and an endless cable connecting each of the superposed pulleys with one of the second-named pulleys, each cable being operatively connected with the adjacent movable section.

6. In an airship, a plane having symmetrical openings at opposite sides of its transverse axis, and movable sections corresponding in size and shape to said openings for covering and uncovering the same; a steering rod and wheel; a vertical shaft; a gear connection between the steering rod and vertical shaft; a pair of superposed pulleys secured to the lower portion of said shaft; a pair of pulleys mounted on the extreme ends of the plane; an endless cable connecting each of the superposed pulleys with one of the second-named pulleys, each cable being operatively connected with the adjacent movable section; a tail stabilizer embodying a fixed section and a movable section adapted to be shifted into or out of overlapping relation to the fixed section to reduce or increase the total surface of the stabilizer; and a cable for operating the second-named movable section and itself operatively related to the vertical shaft.

7. An airship having a tail stabilizer embodying a fixed section, and a movable section adapted to be shifted into and out or overlapping relation to said fixed section to reduce or increase the total surface of the stabilizer, said sections being disposed transversely with respect to the fuselage and out of contact with each other; runners in which the movable section is slidably engaged; a longitudinally arranged control bar connected with said movable section; and a flexible element operatively connected to said bar to shift the same and thereby adjust the position of the movable section.

8. A biplane having an imperforate upper plane, and a lower plane which is provided with symmetrical openings at opposite sides of and parallel with its transverse axis; sections corresponding in size and shape to said openings mounted for sliding movement immediately over the same to gradually cover or uncover them, and thereby increase or decrease the surface area of said lower plane; and operating means for said sections.

9. In an airship, a plane having symmetrical openings at opposite sides of and parallel with its transverse axis and extending substantially the entire width or fore-and-aft distance of the plane; sections corresponding in size and shape to said openings mounted for sliding movement immediately over the same to gradually cover or uncover them and thereby increase or decrease the surface area of the plane; front and rear longitudinal guide bars for said sections mounted upon the

plane at opposite sides of the fuselage and with which the sections are slidably connected; a pair of pulleys mounted upon the extreme ends of the plane; a pair of cables 5 extending substantially parallel with said guide rods and in opposite directions, each cable being operatively connected with one of the movable sections and passing around one of said pulleys; and means for operating the two cables in unison at will independently of the movements of the plane. 10

In testimony whereof I affix my signature.
